UNITED STATES PATENT OFFICE

JOSIAH B. MILLET, MICHAEL J. McCARTHY, AND ARTHUR GRAHAM CAREY, OF CAMBRIDGE, MASSACHUSETTS; SAID McCARTHY AND CAREY ASSIGNORS TO SAID MILLET

AMUSEMENT DEVICE

Application filed January 30, 1932. Serial No. 589,792.

This invention relates to apparatus and method of making smoke rings and has for an object the provision of improvements in this art. The invention was developed to 5 provide an amusement device or toy but may have wider uses.

In order to furnish a full understanding of the nature and objects of the invention it will be described by reference to an illustrative embodiment thereof. This embodiment is shown in the accompanying drawing wherein:

Fig. 1 is an elevational view of the exemplary device in use;

15 Fig. 2 is an enlarged top plan view;

Fig. 3 is a central vertical section;

Fig. 4 is a transverse section taken on the line 4—4 of Fig. 3;

20 Fig. 5 is a transverse section taken on the line 5—5 of Fig. 3;

Fig. 6 is a longitudinal section taken on the line 6—6 of Fig. 3;

25 Fig. 7 is a partial view similar to Fig. 3 but showing a modification.

In making smoke rings with a mechanical device the smoke must first be enclosed in a vessel or container and then be ejected forcibly through an opening thereof into the atmosphere. The smoke may either be generated within the container or be introduced 30 thereinto from outside sources. Ordinarily the latter method proves most convenient since cigar or cigarette smoke which is everywhere available is entirely satisfactory for

35 making rings. Provisions have been made in the present device for expelling air to allow the smoke to be introduced. More perfect rings can be made and they can be made to travel further when they are ejected with a

40 quick movement followed by a sudden stop of the ejecting element. This is provided for in the present device by the use of a stop abutment and associated parts.

45 The present device comprises telescoping cylinders 10 and 11. The cylinders are pressed apart by a spring 12. The spring has sufficient strength to require considerable force in bringing the cylinders together.

50 This gives the speed and impact of parts re-

quired to form good rings and to project them a considerable distance.

The length of stroke in telescoping the cylinders will depend on the size of the opening for the rings and the speed with which the cylinders are moved but in any case is usually relatively short. In the present embodiment the length of stroke is limited at least in the expanding movement and if desired in the contracting movement also by a stop 14 which is secured to one cylinder, as by being passed through a close fitting aperture 15 thereof. The stop has movement relative to the other cylinder as by being passed through an elongated aperture 16 thereof. In the present specific construction the stop means for contracting movement comprises an annular shoulder formed on the bottom of cylinder 10 against which the end of cylinder 11 impinges. The stop means in either case brings the movement of the cylinders to a sudden halt and greatly assists in giving the impact action required for making good rings.

The mounting of the stop 14 which is provided herein furnishes a simple and inexpensive assembly. The stop is attached to a spring finger 17 which can be pressed inward until the stop has cleared the outer aperture 16, thus permitting the cylinders to be completely separated from each other. The spring finger 17 is attached to a split spring ring 18 which fits within the cylinder 10. The ring 18 also provides a support for the coil spring 12. As shown, a ledge 19 is formed on the ring for seating the spring. Preferably the spring finger 17 extends to the bottom of the cylinder so as to place the thrust of the spring thereon. This, of course, is not necessary if the spring ring 18 has sufficient friction with or if it is attached to the cylinder in which it is mounted. The spring 12 when placed near the ring forming hole is made sufficiently large to lie near the circumference of the cylinder where it will not obstruct the free passage of the smoke.

A hole 20 is formed in the end of the lower cylinder 10 for the escape of air when smoke is introduced by way of hole 13. When making rings it is best to keep the hole 20 closed

as by placing the thumb over it. This hole if of proper size may also be used for making rings. In this case the finger is held over the other hole 13. A draft through the container or random eddy currents hinders the formation of rings. Such a disturbance would probably exist if both holes were open at once, although it is possible to make rings at opposite ends simultaneously. Rings are 10 projected by this apparatus so as to have rapid rotation about their annular axes.

A plurality of rings may be formed in a single telescoping action of the cylinders by a pause between successive movements of the 15 cylinders or other ring producing media. This interrupted or intermittent action may be produced in a number of ways. One way is illustrated in Fig. 7. There a series of corrugations 25 is formed on one cylinder to 20 cooperate with a projection 26 on the other cylinder. The size of the corrugations depends somewhat upon the size of the hole used for forming rings, speed of movement and other considerations.

25 From the above description it will be seen that the invention provides an improved device for making smoke rings, which is inexpensive to manufacture, and which can be readily assembled or taken apart for cleaning 30 or repair.

While specific embodiments of the invention have been described particularly it is to be understood that various changes and modifications may be made within the scope of the 35 subjoined claims.

We claim:

1. Apparatus for making smoke rings comprising in combination, a container, mutually 40 movable sides for said container, both sides being movable along a common axis, and an opening in each of said sides.

2. Apparatus for making smoke rings comprising in combination, a container including 45 telescopic cylinders, a spring ring in one cylinder frictionally engaging the wall thereof, a spring support on said spring ring, and a coil spring resting on said support and engaging the other cylinder for urging the telescopic cylinders apart.

50 3. Apparatus for making smoke rings comprising in combination, a container including telescopic cylinders one of which has an opening in one end for forming smoke rings, 55 and a spring for urging said cylinders apart, said spring being disposed within and adjacent the circumference of said cylinders to avoid obstructing the entrance to said opening.

60 4. Apparatus for making smoke rings comprising in combination, a container including telescopic cylinders, a spring ring therein, a coil spring for separating said cylinders resting on said spring ring, a spring finger 65 cured to said spring ring, and a stop on said

finger for limiting the movement of said cylinders.

5. Apparatus as set forth in claim 4 in which said stop passes through aligned holes in the side walls of said cylinders whereby 70 the cylinders may be separated by removal of said stop from said holes.

6. Apparatus as set forth in claim 4 in which said spring finger engages the bottom wall of the cylinder in which said spring ring 75 is mounted.

7. Apparatus for making smoke rings comprising in combination, telescopic cylinders provided with a smoke forming opening, and means to cause said cylinders when moved 80 relative to each other in one direction without reversal to create a series of impulses for forming a plurality of rings, said means including cooperating roughened elements on the cylinders.

In witness whereof, we have signed our names to this specification this 27th day of January, 1932.

JOSIAH B. MILLET.

MICHAEL McCARTHY.

A. GRAHAM CAREY.
